UNITED STATES PATENT OFFICE.

JAMES McCUTCHEON COLEMAN, OF WESTMOUNT, QUEBEC, CANADA.

DUMP-CAR CONSTRUCTION.

1,048,042.

Specification of Letters Patent.

Patented Dec. 24, 1912.

Application filed July 3, 1911. Serial No. 636,702.

To all whom it may concern:

Be it known that I, JAMES McCUTCHEON COLEMAN, resident of 356 Olivier avenue, in the city of Westmount, in the Province of Quebec, in the Dominion of Canada, a citizen of the United States of America, have invented certain new and useful Improvements in Dump-Car Construction; and I do hereby declare that the following is a full, clear, and exact description of the same.

The invention relates to improvements in dump car construction, as described in the present specification and illustrated in the accompanying drawings that form part of the same.

The invention consists essentially in the novel construction and arrangement of the doors closing the dump openings, whereby the joints are absolutely tight and the door readily operated.

The objects of the invention are to improve the conditions in regard to cars used for carrying grain and the like in which the contents of the car are shot out of a chute, and particularly to prevent leakage through the chute openings while the car is traveling.

Further objects are to facilitate the operation of the chute doors on arrival at the elevators, and generally to provide a cheap, simple and durable form of dump car door.

In the drawings, Figure 1 is a longitudinal sectional view of a chute, showing the sliding door and operating mechanism. Fig. 2 is an enlarged detail view of the door, showing the joints. Fig. 3 is a cross section detail of the operating mechanism. Fig. 4 is a sectional detail of the discharge end of the chute with the door removed. Fig. 5 is a vertical sectional view taken on the line C, D, in Fig. 4. Fig. 6 is a vertical sectional view taken on the line A, B, in Fig. 4. Fig. 7 is an underside perspective detail view of the door and operating mechanism detached, with parts broken away.

Like numerals of reference indicate corresponding parts in each figure.

Referring to the drawings, 1 is the chute under the body 2 of the car, said chute terminating in the blank wall 3 at the lower end and having the dump door opening 4 in the bottom thereof at the lower end, said dump door opening being the width of said bottom.

5 is an outturned flange at the lower end of the blank wall 3.

6 is an inturned flange distanced from and parallel with the flange 5 forming a socket.

7 are outturned flanges from the sides of the chute at the door opening 4. 8 are in-turned flanges at the sides of the chute, distanced from and parallel to the flanges 7, both flanges being rigid with said sides. 9 is an out-turned flange at the upper side of said door opening, rigid with the outside surface of the bottom of the chute.

10 is a slide door, having on the lower side thereof, the flanges 12 on the sides and on the lower end respectively and substantially parallel with the surface of said door and terminating substantially flush with the edge thereof, so that said door will slide in the sockets formed by the flanges 7 and 8 and into the socket formed by the flanges 5 and 6.

13 is an inturned flange on the inside of the door at the upper end thereof and parallel with the inside face of the door and adapted to slide into the socket formed by the outturned flange 9, thereby providing a pocket joint at the upper end of the door, the same as the pocket joints at the sides and lower end.

14 is a bracket, centrally secured to the outside face of the door 10, extending parallel with the said outside face. 15 is an arm pivotally secured between the bracket 14 and the outside face of said door 10 by the pivot pin 16, said arm being off-set at 17 and extending upwardly parallel with the bottom of the chute.

18 is a gear of worm wheel form and pivotally secured toward the edge thereof to the upper end of the arm 15, said gear being journaled on the bearing 19, said bearing being rigidly secured to the bottom of the chute or bottom of the car as may be most convenient.

20 is a worm coacting with the gear 18 and mounted on or forming part of the shaft 21, said shaft being journaled in bearings supported by the bracket 22 and extending across to the sides of the car, there being operated by the crank 23.

It will be thus seen that a very complete construction is provided, particularly for sliding doors covering dump openings, as by means of the crank 23, the worm 20 is turned and thus coacting with the said gear 18, the latter is operated, which swings the upper end of the arm around and draws it

farther up the chute, thus the door 10 is slid upwardly in the slideways formed by the flanges 7 and 8.

In closing the door, the crank is turned in 5 the reverse direction and practically the same operation occurs, that is to say, the door slides along, though downwardly, and when driven to the home position, the double set of flanges form pocket joints through 10 which even the finest granulated cargo cannot leak out.

What I claim as my invention is:

1. In car construction, a chute secured to the body of the car and terminating in a 15 blank wall at the end thereof and having a dump opening through the bottom thereof at the lower end, flanges rigidly secured around said opening and forming, with said chute walls, surrounding pockets to said 20 door opening, a door of double plate formation at the edges thereof forming pockets completely therearound, and means for operating said door in and into the aforesaid pockets surrounding the chute opening.
- 25 2. In car construction, a chute secured to the body of the car having a blank wall at the lower end thereof and a dump opening through the bottom thereof adjacent to said blank wall, an outturned double plate formation at the lower end of said blank wall, outturned double plate formations from the 30 side walls of said chute at said dump opening, and an outturned double plate formation on the bottom of said chute at the upper

end of said dump opening, a door having at 35 the lower end a double plate formation co-acting with the double plate formation at the lower end of said blank wall in effecting the joint, and double plate formations on the sides thereof coacting with the double 40 plate formations on the sides of the dump opening and an inturned double plate formation at the upper end thereof co-acting with the outturned double plate formation at the upper end of the chute opening, and 45 means for operating said door.

3. In a car construction, a chute having a blank wall, a dump-opening in said chute, a door having at its lower end a double plate formation coacting with a double plate 50 formation at the lower end of said blank wall to form a joint and a double plate formation on the sides thereof coacting with the double plate formations on the sides of the dump opening to form a joint and an 55 inturned double plate formation at the upper end of said door coacting with an outturned double plate formation at the upper end of said chute opening, and means for operating said door. 60

Signed at the city of Montreal, Province of Quebec, Canada, this twelfth day of June, 1911.

JAMES McCUTCHEON COLEMAN.
